UNITED STATES PATENT OFFICE.

CHARLES F. SMITH, OF NEW BRITAIN, CONNECTICUT, ASSIGNOR TO THE LANDERS, FRARY & CLARK, OF SAME PLACE.

DESIGN FOR A KNIFE-HANDLE.

SPECIFICATION forming part of Design No. 32,148, dated January 30, 1900.

Application filed December 16, 1899. Serial No. 740,603. Term of patent 14 years.

To all whom it may concern:

Be it known that I, CHARLES F. SMITH, a citizen of the United States, residing in New Britain, in the county of Hartford and State 5 of Connecticut, have invented and produced a new and original Design for a Knife-Handle, of which the following is a specification, reference being had to the accompanying drawings, in which—

10 Figure 1 is a side elevation of a knife-handle, showing my design. Fig. 2 is a transverse section of the same on the line $x x$ of Fig. 1.

As shown in the drawings, each side has a 15 plain flat middle portion 3, surrounded by a beveled edge having longitudinal beads 4, which extend around the butt of the handle. A portion of the blade is indicated in broken

lines as extending from the said handle. The front end 5 of the handle on each side is plain. 20 The contour of the complete handle at the line $x x$ of Fig. 1 is shown by the sectional view, Fig. 2. On the plain flat middle portion 3, near the front end, there is a circular projection 6, with a face having a rounded 25 form.

Having described my invention, what I claim as new, and desire to secure by Letters Patent, is—

The design for a knife-handle as herein 30 shown and described.

CHARLES F. SMITH.
